UNITED STATES PATENT OFFICE.

PERLE E. TROUTMAN, OF KANSAS CITY, KANSAS.

DESIGN FOR AN OIL STOVE OR BURNER.

45,246.

Specification for Design.

Patented Feb. 10, 1914.

Application filed November 20, 1913. Serial No. 802,165. Term of patent 7 years.

To all whom it may concern:

Be it known that I, PERLE E. TROUTMAN, a citizen of the United States, residing at Kansas City, in the county of Wyandotte, State of Kansas, have invented a new, original, and ornamental Design for Oil Stoves or Burners, of which the following is a specification, reference being had to the accompanying drawing, forming a part thereof.

The figure is a perspective view of an improved oil stove or burner showing my new design.

I claim:

The ornamental design for an oil stove or burner, as shown.

In witness whereof I hereto affix my signature in the presence of two witnesses.

PERLE E. TROUTMAN.

Witnesses:

HELEN C. RODGERS,
GEO. Y. THORPE.
